UNITED STATES PATENT OFFICE.

JOHN C. TATE, OF OAKLAND, CALIFORNIA.

GAS-BURNING HEATER.

1,349,862.

Specification of Letters Patent. Patented Aug. 17, 1920.

Application filed March 4, 1918. Serial No. 220,157.

To all whom it may concern:

Be it known that I, JOHN C. TATE, a citizen of the United States, and a resident of the city of Oakland, county of Alameda 5 and State of California, have made a new and useful invention—to wit, Gas-Burning Heaters; and I do declare the following to be a full, clear, exact, and concise description of the same.

10 The invention relates particularly to gas burning heaters of the type disclosed in my United States Letters Patent, No. 1,181,552, dated May 2, 1916.

15 Among the objects of the invention are to render available all of the heat units contained within the fuel, to reprocess and re-normalize the products of combustion, whereby none but innocuous fumes escape from the heater dispensing with outside flues or vents, 20 rendering the heater one hundred per cent. efficient by transmuting all of the heat units of the fuel into available calories for radiation. Other objects and advantages will appear as this description progresses.

25 In this specification and the annexed drawings, the invention is illustrated in the form considered to be the best, but it is to be understood that the invention is not limited to such form because it may be embodied in other forms, and it is also to be understood that in and by the claim following the description it is desired to cover the invention in whatever form it may be embodied.

35 In the accompanying one sheet of drawings:

Figure 1 is a side view in cross section taken on the line I—I, Fig. 2, of a renormalizing gas heater constructed in accordance with this invention.

40 Fig. 2 is a front view of the same in cross section on the lines II—II, Fig. 3.

Fig. 3 is a cross section of the same taken on the lines III—III, Fig. 2, looking down 45 into the heater.

In detail the construction illustrated in the drawings includes an iron gas heater of the radiator type, having a central primary combustion chamber 1, with an open bottom 50 at 2, for the admission of atmospheric air as contained within the room to be heated. The gas burner 3 of the Bunsen type is located near the bottom of the combustion chamber. The burner has the air control 55 inlet 4 and the gas supply pipe 5, controlled by the valve 6, for the admission of natural

or manufactured gas mixed with air and liberated through the openings 7, where it may be conveniently ignited through the opening 8 in the front of the combustion chamber, 60 by the introduction of a lighted match or taper in the usual manner. A similar opening 9 is provided for observation. Burners of this type consuming natural gas or gases made from oil or coal and other carbons, 65 give off a clear blue smokeless flame but contain noxious elements, which it is one of the objects of this invention to normalize or neutralize. The flames issuing from the holes 7 impinge against the adjacent walls 70 of the combustion chamber at 10 and 11, transmitting a relatively high degree of heat thereto in a localized area. The products of combustion pass upward and out of the central combustion chamber through the openings 12 and 13, thence downward through the circulating tubes 14 and 15, passing out of the bottom of these or through the openings 16 and 17, into the reheating chambers, 75 arranged contiguous to and surrounding the 80 hot walls 10 and 11 adjacent to the zone of the burner 3, preferably separated therefrom only by the walls of the combustion chamber. The reheating chambers intercommunicate through the rear chamber 19, closed at 85 the top by the wall 20 and at the bottom by the partition 21 and from which the products of combustion escape through the flanged opening 22. This outlet 22 leads to the revivifying chamber 23 consisting of a 90 box-like structure having an opening inclosing the outlet 22 overspread by the screen 24, and having the outlet 25 facing inward toward the wall 26 of the combustion chamber. The revivifying chamber 23 is fastened to the body of the radiator by the bracket 27. This revivifying chamber 23 is filled with a revivifying compound 28 fabricated into balls or lumps adapted to permit the free circulation there among of the 95 products of combustion passing through the chamber 23.

In connection with the revivifying compound, attention is directed to my co-pending application for patent entitled "Absorbing and purifying composition", Ser. No. 121,482, filed Sept. 22, 1916.

This invention operates substantially as follows: The products of combustion rising from the burner 3 and returning through 110 the tubes 14 and 15 to the reheating chambers, are heated and processed therein.

The reheating causes a rarefaction or suction, similar to that caused within a chimney or flue after it becomes thoroughly heated, resulting in a thermo-siphon effect drawing a large volume of normal air through the opening 2, past the deflector 2', at the bottom of the combustion chamber, which rises and mingles with the products of combustion, causing a draft through the 10 radiator that will eventually circulate all of the air within a closed room through the heater, thus raising the temperature of the whole volume by absorption of heat given off by the heater. The products of natural 15 and commercial gas for combustion are known to contain noxious fumes, and a large volume of moisture that is decomposed within the heater and hydrogen is formed; this aids in preventing the condensation on the cold walls of the room, an economic disadvantage that is wholly eliminated by this invention, partly by contact with the hot walls 10 and 11 of the reheating chambers, by absorption in the compound 28, and by being liberated through the outlet 25 directly against the heated wall 26 of the combustion chamber. This recontacting of the products of combustion with surfaces of relatively high temperature 25 has the double advantage of drying the air and increasing the speed of thermo-circulation or the siphoning effect through the heater. Perfect combustion within the heater is insured by the reheating or secondary combustion within the reheating chambers, yet there still remains the noxious fumes resulting even from perfect combustion that can not be disposed of as waste products, because of their calorific value, 30 but which I have demonstrated can be neutralized and the atmosphere completely revivified without appreciable economic loss. This chemicalization is accomplished by the compound 28.

40 Without in any way limiting the scope of my invention and discovery, the following explanation of the phenomena is offered as tending to a better understanding of the invention, that is now a demonstrated success and in wide commercial use.

45 The resultant action of the products of combustion of gas containing sulfurous combinations, coming from the combustion chamber and mixed with the excess of normal atmosphere passing through the opening 2 and adjacent to the gas flame, is a combination that acts on the iron of the radiator, and produces oxids. The mass-body of gases of combustion, sulfuretted moisture 50 of burned gas, and the unchanged heated atmosphere pass through the reheating chambers 18, wherein hydrogen may be formed or a second combustion occur. Then the further massed body of combustion 55 gases and empyreuma pass to the chamber

23 carrying the said oxids in atmospheric suspension, depositing them in the compound 28 by the precipitating action due to the separation of the oxygen of the unchanged heated atmosphere, thereby liberating free oxygen and possibly a very slight formation of ozone.

The action taking place in the pores of the compound 28 is dual. First, the separation of oxygen from the atmosphere and the precipitation of the oxids, but the prime object in this case is to destroy the precipitated oxidized empyreuma of combustion, due to oxidation and decomposition occurring in the central parts of the radiator and 80 recombustion chambers.

The partial decomposition of the moisture driven off in the combustion of fuel in the combustion chamber takes place in the reheating chambers in the following manner. The uncombusted results and the moisture of the gas fuel after semi-oxidation in the iron radiator comes in contact with the hot partitions 10—11 between the primary combustion chamber and the reheating chambers, hydrogen is produced, and the heat created is sufficient to complete the primary combustion and further deodorize the fumes produced by the primary combustion, and put them in a state susceptible to chemical change by the compound 28 in the purifying chamber, which is the final revivification of the atmosphere taken in at the inlet 2 of the combustion chamber.

The sensed freshness of the heated atmosphere coming from the outlet 25 of the compound chamber is due to the presence of free oxygen produced by the compound, which has the capacity of burning up the organic gases in the air, then resuming its normal relation in the atmosphere. This interpretation seems to be substantiated by the fact that the compound increases in weight, which is the combined result of oxidization, decomposition and absorption, and the further fact that there are no odors or noxious fumes emitted. This compound is trifling in first cost, and will retain its capacity throughout six months or more of continuous operation. The revivification is more perfect in combination with the reprocessing of the products of combustion in the reheating chambers, but the re-combustion chamber could be omitted if combustion is completed within the combustion chamber, 120 which is in a measure dependent upon the quality of fuel consumed.

Having thus described my invention, what I claim and desire to secure by Letters Patent is:

In a heater of the character described, an upstanding combustion chamber provided at its lower end with an air inlet, a burner extending transversely within the lower portion of the combustion chamber and hav-

ing sets of apertures arranged upon the opposite sides of its longitudinal axis for providing flames which impinge against the sides of said combustion chamber, upstanding tubes arranged outwardly of and near the combustion chamber and having their upper ends in communication therewith while their lower ends are free from communication with the combustion chamber, reheating chambers arranged contiguous to the side walls of the combustion chamber, said extensions having their lower ends open and in communication with the lower ends of said tubes, and a revivifying chamber connected with the reheating chambers 15 and receiving the highly heated gases therefrom, said revivifying chamber being adapted for the reception of chemical material and having an outlet opening near its top and upon the inner side thereof adjacent 20 the heated wall of the combustion chamber.
